UNITED STATES PATENT OFFICE

1,922,653

DEBIT AND CREDIT SHIFT MECHANISM
FOR BOOKKEEPING MACHINESWalter Adelbert Anderson, Rockford, Ill., assignor
to Sundstrand Corporation, of Wilmington,
Del., a Corporation of Delaware

Application October 16, 1929. Serial No. 399,931

10 Claims. (Cl. 197—177)

This invention relates to computing and printing machines especially adapted for operating upon one or more work pieces including, usually,

5 a ledger sheet. Such a machine comprises a relatively long paper carriage to support the work sheet or sheets, the carriage being laterally movable and being equipped with tabulating devices to effect stoppage of the carriage in the different columnar positions and to cause the machine to perform the necessary functions in each columnar position. For one example of such a machine, reference may be made to application Serial No. 118,628, filed June 26, 1926 by Oscar J. Sundstrand.

10 In the use of such a machine it is customary for the operator to enter all items of a certain class, as, for example, all the debit items, and then enter the items of the other class, as, for example, the credit items. Since these classes of items are entered in different columns on the ledger sheet a different arrangement of tabulating devices is required when posting debits than when posting credits. This necessity has heretofore been met either by readjusting the tabulating devices on the paper carriage at the conclusion of the operation of posting debits, or by employing two separate carriers adapted to be interchangeably attached to the paper carriage, one carrier being equipped with the tabulating devices which are needed during the posting of debits and the other carrier being equipped with the tabulating devices which are required when posting credits.

15 It has also been proposed to use a carrier in the form of an elongated plate hinged to the paper carriage at one of its longer edges, said plate having upon its lower side pins adapted to cause the operations necessary for both classes of postings, means being provided to tilt the plate upwardly to render the distinctively credit-controlling devices ineffective during the posting of debits and for tilting the plate upwardly to render the distinctively debit devices ineffective during the posting of credits. The present invention relates to simple and convenient means for readily controlling the operation of the plate for the performance of the desired class of operations.

20 In the accompanying drawing:

Figure 1 is a fragmental right-hand side elevation of a bookkeeping machine embodying the features of my invention, the parts being shown in position for the performance of one class of posting operations.

Fig. 2 is a detail view of a control plate which is specifically different from the one illustrated in Fig. 1.

Fig. 3 is a view similar to Fig. 1, but showing the parts adjusted for posting the other class of items.

25 The laterally movable paper carriage 1 has an elongated control plate 2 pivoted to the carriage to swing upon the axis 3. For a full disclosure of such a control plate, reference may be made to the Sundstrand application Serial No. 118,628. A roller 4 on the machine frame is adapted to support the rear edge of the control plate. On the lower side of the 30 control plate are located transverse rows of stop pins 5, as more fully disclosed in said Sundstrand application. These stop pins coact with a group of devices (not shown) located on the machine frame.

35 In the specific form of control plate illustrated in Fig. 2 (and disclosed more fully in application Serial No. 420,328 filed January 13, 1930) a series of control blocks 5' are employed to produce the desired combination of machine operations in the respective columnar positions of the carriage. Each of the several control blocks 5' is the equivalent of one of the transverse rows of pins employed in the construction illustrated in Fig. 1, the several blocks being adjustably and removably attached to the control plate for the purpose of facilitating adjustment of the machine to different classes of work.

40 In practice, there is one such row of stop pins for each columnar position required in the posting of debits and a row of stop pins for each columnar position required in the posting of credits. Some of these rows of stop pins are employed in both classes of posting, whereas 45 others are used only in debit posting and still others only in the posting of credits. In order that the rows of stop pins which are distinctive to credit posting shall not coact with the control devices on the machine frame during the 50 posting of debits, and vice versa, I provide the means to be now described.

45 Each of the distinctively debit rows of stop pins has associated therewith a lug 6 arranged adjacent to the rear edge of the control plate 55 to travel in a certain plane as the paper carriage makes its working stroke. Associated with each distinctively credit row of stop pins is a similar lug 7 attached to the control plate near the rear edge of the latter to travel in a path 60

different from the path taken by the lugs 6. The lugs 6 and 7 are beveled at their forward sides so as to be adapted to engage a roller 8 supported on the machine frame and thus cause the control plate to tilt upwardly as the lug is riding over said roller and thereby cause the corresponding row of stop pins to jump over the control devices on the machine frame, the paper carriage proceeding to the next columnar position. The roller 8 is supported so that it may be moved into the path of either the lugs 6 or the lugs 7. Herein is shown a slide 9 which is guided on the machine frame by means of a guide pin 10 and a guide screw 11. Said slide is mounted for movement in a line parallel to the plane occupied by the control plate 2 when the latter rests upon the supporting roller 4. The roller 8 is mounted on an upstanding portion 12 of the slide 9.

20 The means for moving the slide 9 comprises a lever 13 pivoted in the machine frame at 14, the upper arm of said lever having a pin-and-slot connection with the slide. The other arm of the lever is connected by means of a link 15 to a hand lever 16 pivoted in the machine frame at 17, said hand lever having a handle 18. It will be seen that reciprocation of the hand lever 16 will cause reciprocation of the slide 9.

In order to locate the roller 8 definitely in either of its two positions and hold the roller in adjusted position during operation, I provide means, as, for example, a detent 19 pivoted at 20 in the machine frame, said detent having two notches 21 to receive a pin 22 on the lever 13. 35 A contractile spring 23 holds the detent 19 in engagement with the pin, but permits the detent to yield to allow the pin to move from one to the other of the notches when the lever 16 is manipulated.

40 The operation will be clear upon the foregoing description. Before the posting of debits is begun, the roller 8 is adjusted into position so as to engage the lugs which are associated with the distinctively credit sets of stop pins. When credits are to be posted the roller 8 is moved into its other position wherein it is engaged by the lugs associated with the distinctively debit sets of stop pins.

It will be seen that it is a very simple matter 50 to adjust the tabulating devices for the performance of the two classes of bookkeeping entries. The hand lever 16 is located at the right-hand side of the machine where it is in plain sight and within convenient reach of the operator.

In the following claims I have used the term 55 "transverse row of control elements" to denote a row of stop pins 5 as in Fig. 1 or a block 5' as in Fig. 2 or any equivalent construction.

I claim as my invention:

1. In combination with a machine of the class described, a paper carriage, a control plate pivoted to said paper carriage, parts on said plate arranged to travel in different paths, a member on the machine frame movable into position to be engaged by the parts which travel in one path and also being movable into position to be engaged by the parts traveling in the other path, said parts being arranged to ride over said member in the travel of the paper carriage and thus raise the control plate into inoperative position, and manipulative means located at the side of the machine for adjusting said member into either of its two positions.

2. The combination with a computing machine of a paper carriage, a control element movably connected to said paper carriage, parts on said element arranged to travel in different paths, a member on the machine frame movable into position to be engaged by the parts which travel in one path and also being movable into position to be engaged by the parts traveling in the other path, said parts being arranged to ride over said member in the travel of the paper carriage and thus move the control element into inoperative position, and manipulative means located at the side of the machine for adjusting said member into either of its two positions.

3. The combination with a computing machine of a paper carriage, a control plate pivoted to said paper carriage, two beveled lugs on said plate arranged to travel in different paths, a member on the machine frame to be engaged by said lugs, said lugs being arranged to ride over said member in the travel of the paper carriage and thus raise the control plate into inoperative position, and manipulative means located at the side of the machine for causing relative adjustment of said lugs on the one hand and said member on the other hand, to establish operative relation between said member and either lug.

4. In combination with a computing machine 105 and the laterally movable carriage thereof, control means connected to said carriage to effect operation of said machine in predetermined lateral positions of said carriage, and manipulative means effective in one position to render 110 said control means ineffective in a selected one of the predetermined lateral positions of said carriage and effective in a second position to render said control means ineffective in a selected position of said carriage different from 115 said first mentioned selected position.

5. In combination with a computing machine of the class described having a laterally movable carriage, sets of machine-control means connected to said carriage for lateral movement therewith, said control means being adapted to condition said machine for operation in predetermined lateral positions of said carriage, a plurality of parts on said carriage, each of said parts corresponding with a certain one 125 of said sets of machine-control means, and a relatively stationary member to coact with said parts, said member being adjustable to coact with selected ones of said parts to disable said machine-control means in corresponding positions of said carriage.

6. A bookkeeping machine comprising, in combination, a laterally movable paper carriage, a control plate operably connected to and movable with said carriage, means on said control 135 plate to condition said machine for operation in predetermined lateral positions of said carriage, lugs on said control plate in positions corresponding with predetermined ones of said conditioning means, said lugs being arranged to 140 travel in paths spaced from one another, a member on the machine frame, lever means effective to move said member into the path of movement of either of said lugs, and manipulative means effective to actuate said lever 145 means.

7. In combination, a bookkeeping machine having a laterally movable carriage, a control plate movable with said carriage, said plate having transverse rows of control elements, each row 150

- corresponding to a predetermined columnar position of said carriage, said elements being adapted to effect control of said machine in said columnar positions, settable means adapted to 5 occupy two positions of adjustment, and parts on said control plate each corresponding to a single columnar position, said settable means being effective to cooperate with said parts to disable the control elements in the corresponding 10 columnar positions of the carriage.
8. In combination, a bookkeeping machine having a laterally movable carriage, a control plate movable with said carriage, said plate having transverse rows of control elements, each row 15 corresponding to a predetermined columnar position of said carriage, said elements being adapted to effect control of said machine in said columnar positions, settable means adapted to occupy two positions of adjustment and parts 20 on said control plate rearwardly of certain ones of said transverse rows of control elements, said settable means being effective to cooperate with said parts to disable the control elements in the corresponding columnar positions of the carriage. 25
9. In combination, a bookkeeping machine 30
- having a laterally movable carriage, a control plate movable with said carriage, said plate having transverse rows of control elements, each row 35 corresponding to a predetermined columnar position of said carriage, said elements being adapted to effect control of said machine in said lateral positions, and settable means effective in one position of adjustment to disable said control elements in a selected one of the predetermined lateral positions of said carriage and effective in a second position of adjustment to disable said control elements in a second one of the predetermined lateral positions of said carriage. 40
10. In combination, a bookkeeping machine having a laterally movable carriage, means connected to and movable with said carriage, said means corresponding to a plurality of columnar positions of said carriage, and being effective to control said machine in said positions, and means including a manipulative element adjustable to two positions to disable said first mentioned means in either of two of said columnar positions. 45
